(57) **CLAIM**

The ornamental design for a handle for starter pull cords, as shown and described.

DESCRIPTION

FIG. 1 is a perspective view of a handle for starter pull cords showing my new design;

FIG. 2 is a side view thereof taken from the left;

FIG. 3 is a front view thereof;

FIG. 4 is a rear view thereof;

FIG. 5 is a bottom view thereof; and,

FIG. 6 is a top view thereof.

The broken lines shown represent unclaimed subject matter and form no part of the claimed design.
